[57] **CLAIM**

The ornamental design for a bicycle front fork suspension lower tube, as shown and described.

DESCRIPTION

FIG. 1 is a front perspective view as seen from the right front side of a left front fork suspension lower tube showing my design (a right front fork suspension lower tube being the mirror image thereof);

FIG. 2 is a right side elevational view of the design for a left front fork, suspension lower tube, a corresponding view of a right front fork suspension lower tube being the mirror image thereof;

FIG. 3 is a bottom plan view of the design for a left front fork suspension lower tube, a corresponding view of a right front fork suspension lower tube being the mirror image thereof;

FIG. 4 is a top plan view of the design for a left front fork suspension lower tube, a corresponding view of a right front fork suspension lower tube being the mirror image thereof;

FIG. 5 is a right elevational view of the design for a right front fork suspension lower tube, a corresponding view of a left front fork suspension lower tube being the mirror image thereof;

FIG. 6 is a rear elevational view of the design for a left front fork suspension lower tube, a corresponding view of a right front fork suspension lower tube being the mirror image thereof; and,

FIG. 7 is a front elevational view of the design for a left front fork suspension lower tube, a corresponding view of a right front fork suspension lower tube being the mirror image thereof.
